CALCULATING MACHINE

Otto Koch, Brunswick, Germany, assignor to
 Brunsiga-Maschinenwerke Grimme, Natalis &
 Co. Aktiengesellschaft, Brunswick, Germany

Application August 22, 1932, Serial No. 629,941,
 and in Germany September 3, 1931

6 Claims. (Cl. 235—79)

My invention relates to improvements in calculating machines, and more particularly in calculating machines of the type comprising setting disks adapted to be axially shifted into and out

5 of engagement with the numeral wheel operating devices and carrying laterally directed stepped teeth the desired number of which is brought into position for acting on the numeral disks.

The object of the improvements is to provide a 10 calculating machine of this type by means of which products of several factors may be taken and other calculations performed without setting intermediate products by means of the keys on the said setting disks.

15 With this object in view my invention consists in providing a mechanism intermediate the numeral disks and the said setting disks by means of which the intermediate results may be carried from the numeral disks to the said setting disks without acting on the key

20 or other mechanism, so that by means of the said number transferred from the numeral disks to the setting disks multiplications and any other calculations may be made. Another object of the improvements is to provide a mechanism for 25 transferring the intermediate results from the numeral disks to the setting disks which is simple in construction and reliable in operation.

For the purpose of explaining the invention an example embodying the same has been shown in 30 the accompanying drawings, in which the same letters of reference have been used in all the views to indicate corresponding parts. In said drawings

Fig. 1 is a sectional elevation of the machine 35 showing a part only of the keyboard and the key mechanism,

Fig. 2 is a sectional plan view taken on the line 2—2 of Fig. 1,

Fig. 3 is a partial sectional elevation taken on 40 the line 3—3 of Fig. 1,

Fig. 4 is a sectional plan view taken on the line 4—4 of Fig. 1, and

Fig. 5 is an elevation showing two cam disks 45 used in the mechanism for transmitting the values from the numeral disks to the setting disks.

In the following I shall describe a calculating machine of the construction shown and described in the application for patent of Haase, Ser. No. 595,913, filed February 29, 1932.

50 As shown in the figures the casing of the machine comprises a base plate 1 and side walls 2 in which the main driving shaft 3 is mounted. To the said driving shaft 3 setting disks 4 and 5, two for each order, are secured, and the setting disks 4 are provided with four laterally directed

stepped teeth 55 of different lengths, while the setting disks 5 are provided with five teeth 56 of equal length. For entering the value into the machine the setting disks 4 and 5 are shifted in axial direction towards each other and with 60 their teeth into position for engagement with intermediate gear wheels 6 connected with the numeral disks 7. For thus shifting the setting disks keys 50 or similar hand-operated devices are provided. In the figures only three keys 50 65 of the columns have been shown, which keys represent the figures 1, 8 and 9. At its bottom end the stem 51 of each key lever is provided with a fork 52 downwardly directed arms 53 formed with bevelled faces 8 and 9. The said 70 faces are in engagement with lugs or noses 13 formed on bars 10 and 11 rockingly mounted on pivot bolts 12. The said bars 10 and 11 are made integral with upwardly directed arms 54 bearing on the outer side faces of the setting disks 4 and 5. 75 Between the said setting disks a spring 14 is provided which tends to force the said disks outwardly and out of engagement with the numeral wheel 6, as is shown in Fig. 2. When one of the keys 50 is depressed one or both bars 10 and 11 80 are rocked by means of the bevelled faces 8 and 9 in a direction for shifting the setting disks 4 and 5 towards each other and with their teeth 55 and 56 into engagement with the intermediate gear wheel 6. As has been described in detail in 85 the aforesaid prior application for patent and has been indicated in Fig. 3, the noses 13 of the bar 10, which correspond to the keys 1, 2, 3 and 4 of each column are in stepped relation, so that the bars 10 are rocked thereby through different 90 angles according to the key which has been depressed. Thus by the said bevelled faces 8 the setting disks 4 are adapted to be set into four 95 different positions in which either one, two, three or four teeth 55 are in position for engaging the numeral wheel 6. The noses 13 of the bars 11 are alike in construction and they are adapted to shift the setting disks 5 into one position only in which all the teeth of the said setting disks 100 are in position for cooperation with the intermediate gear wheels 6. The figures 1, 2, 3 and 4 are entered into the machine by shifting the setting disk 4, the figure 5 is entered into the machine by only shifting the setting disk 5, and the figures 6, 7, 8 and 9 are entered into the machine 105 by shifting both setting disks. For this purpose the noses 13 corresponding to the keys representing the figures 1 and 6 are bent laterally so far that the setting disk 4 is shifted in axial direction one step and so that only the longest tooth 55 gets 110

into position for engagement with the intermediate gear wheel 6, the noses corresponding to the figures 2 and 7 are bent outwardly so far that the said setting disk 4 is shifted two steps, so that 5 two teeth get into position with the intermediate gear wheel 6, the noses 13 corresponding to the figures 3 and 8 are bent so far that three teeth 55 get into operative position, and the noses 13 corresponding to the figures 4 and 9 are bent 10 so far that all the teeth 55 get into operative position. The noses 13 of the bars 11 are bent laterally only at the keys representing the figures 5, 6, 7, 8 and 9 and so far that they shift the setting disk 5 one step. Thus, for transmitting 15 the numbers from 1 to 4 into the machine only the setting disk 4 is shifted, for transmitting the number 5 into the machine only the setting disk 5 is shifted, and for setting the numbers from 6 to 9 into the machine both setting disks 4 and 20 5 are shifted. For locking the keys in depressed positions a locking device 15 is provided, and for resetting the keys the said locking device 15 is thrown out of operation by means of a cam member 17 shifted by a resetting key 16, whereupon 25 the depressed keys and the setting disks 4 and 5 are returned into initial positions.

For mechanically transferring the numbers set on the numeral disks 7 of the main counting mechanism to the setting mechanism 4, 5 the following mechanism is provided: The gear wheels 57 of the numeral disks 7 are in mesh with gear wheels 19 rotatably mounted on a shaft 18, and to the hubs 20 of the said gear wheels 19 cam disks 21 and 22 are secured. The cam disks 21 30 are arranged in four steps of different radii and corresponding to the numbers from 1 to 4 and 6 to 9, while the cam disk 22 has a single step for the numbers from 5 to 9. The said cam disks cooperate with slides 23 and 24 guided in 35 slots of transverse walls 58 and 59 and acted upon by springs 25 tending to shift the same forwardly and into engagement with the cam disks 21 and 22. Normally the slides are held out of engagement with the cam disks by pins 26 fixed to a 40 rock shaft 27. To the said rock shaft a hand lever 28 is secured which is acted upon by a spring 29 tending to rock the same rearwardly and with the pins 26 into engagement with arms 60 secured to the slides 23 and 24. When 45 the hand lever 28 is rocked forwardly, in Fig. 1, the pins 26 release the slides 23 and 24 and the springs 25 shift the said slides forwardly and into engagement with the cam disks 21 and 22. To the rear ends of the slides 23 and 24 bars 30 50 are secured which project downwardly therefrom and into position for engagement with pins 31 secured to slides 32 and 33. Normally the said slides 32 and 33 are pulled rearwardly by springs 34, so that the pins 31 bear on the bars 55 30. The slides 32 are formed each with four notches and shoulders 61, and the slides 33 each with a single shoulder, and the said shoulders are engaged by spring pawls 35 secured to a 60 rock shaft 36. When the hand lever 28 is rocked 65 forwardly for releasing the slides 23, 24 the said slides and the slides 32, 33 are pulled forwardly, and when the hand lever 28 is released and rocked rearwardly by the spring 29 the slides 23 and 24 are likewise rocked rearwardly by the pins 26, 70 while the slides 32 remain in projected positions in which they are locked by the pawls 35. When the slides 32 and 33 are shifted forwardly they slide on inclined cam faces 37 and 38 of the bars 10 and 11, and they shift one or both setting disks 75 4 and 5 towards each other and into positions

for engagement with the intermediate gear wheels 6. It will be understood that the bars 10 are rocked through a greater or smaller angle according as the slides 32 and 33 are allowed to be projected more or less by the springs 25 and the steps of the cam disks 21, so that the number set on the numeral disk 7 and corresponding to the operative step of the cam disk 21 is transmitted to the corresponding setting disk 4, and the slide 33 will be shifted sufficiently for engaging the cam 38, or it will not be so shifted, according to the number appearing in the corresponding numeral disk. During this transferring operation the keys and their mechanisms are not acted upon. If now the main shaft 3 is rotated, the number carried into the setting apparatus is entered into the calculation in the same way as if the said value had been set by means of the keys. The setting disks 4 and 5 are reset by means of the resetting key 16. At its bottom end the stem 62 of the said resetting key 16 carries a cam 39 which cooperates with a rail 40 acted upon by a spring 41 and connected with an arm 63 secured to the shaft 36. When the key 16 is depressed the cam 39 shifts the rail 40 rearwardly 95 in opposition to the spring 41, so that the pawls 35 are retracted from their shoulders, and the bars 32, 33 are retracted from the cam faces 37 and 38 by the springs 34, whereupon the bars 10 and 11 and the disks 4 and 5 are returned into 105 initial positions by the springs 14.

When the hand lever 28 is operated for transferring the number set on the numeral wheels to the setting disks 4 and 5, and the said setting disks are still in operative positions for transmitting a number set thereon by the keys, a wrong figure might appear in the setting disks at the end of the transferring operation by means of the lever 28. Therefore, at the beginning of the rocking movement of the hand lever 28 the 110 keys are first reset, and for this purpose one of the pins 26 fixed to the rock shaft 27 forces a rod 42 forwardly, which rod is formed at its front end with a bevelled face 43 adapted to engage a lug 64 secured to the comb 17 and to shift the 115 said comb laterally and in a direction for throwing the locking devices 15 out of locking engagement with the keys.

I claim:

1. In a calculating machine, the combination, 125 with the registering mechanism, axially shiftable setting disks adapted to be brought by axial displacement into position for cooperation with said registering mechanism, and means for axially shifting said setting disks, of means controlled 130 by the registering mechanism for shifting said setting disks in accordance with the numbers on the registering mechanism, and manual means for allowing said means controlled by the registering mechanism to be thrown into operation. 135

2. In a calculating machine, the combination, 140 with the registering mechanism, axially shiftable setting disks adapted to be brought by axial displacement into position for cooperation with said registering mechanism, and hand-operated means 145 for axially shifting said setting disks, of stepped cam disks rotatable with said registering mechanism, means controlled by said stepped cam disks for axially shifting said setting disks into position for cooperation with said registering 150 mechanism, and hand-operated means for allowing said second-named means to be thrown into operation.

3. In a calculating machine, the combination, 155 with the registering mechanism, axially movable

- setting disks cooperating with said registering mechanism for transmitting values thereto, hand-operated means for axially shifting said setting disks including rockable members engaging the side faces of said setting disks and formed with cam members, of stepped cam disks in driving engagement with said registering mechanism, means intermediate said cam disks and said bevelled cam members adapted to engage 5 said cam members and to rock said rockable members in accordance with the position of said cam disks, and manual means for controlling the operation of said intermediate means.
4. In a calculating machine, the combination, 10 with the registering mechanism, axially shiftable setting disks adapted to be brought by axial displacement into position for cooperation with said registering mechanism, and hand-operated means for axially shifting said setting disks, of 15 means controlled by the registering mechanism for shifting said setting disks in accordance with the numbers on the registering mechanism, automatic means for locking said means in position, manual means for throwing said locking means 20 out of operation and manual means for rendering operative said means controlled by the registering mechanism.
5. In a calculating machine, the combination, 25 with the registering mechanism, axially shiftable setting disks adapted to be brought by axial
- displacement into position for cooperation with said registering mechanism, and hand-operated means for axially shifting said setting disks, of means intermediate said registering mechanism and setting disks for transmitting values from 30 said registering mechanism to said setting mechanism, said means comprising two portions one controlled by said registering mechanism and the other one loosely engaged by said first-named portion, automatic means for locking said loosely engaged portion in one position, manual means for throwing said locking means out of operation, and manual means for controlling the operation of said portion directly connected with the registering mechanism.
6. In a calculating machine, the combination, 35 with the registering mechanism, axially shiftable setting disks adapted to be brought by axial displacement into position for cooperation with said registering mechanism, and hand-operated means for axially shifting said setting disks, of means controlled by the registering mechanism for shifting said setting disks in accordance with the numbers carried thereby, hand-operated means for controlling the action of said means 40 controlled by the registering mechanism, and mechanism connected with said last-named hand-operated means for resetting said first-named hand-operated means.
